UNITED STATES PATENT OFFICE

HAROLD HARGREAVES, OF BURNLEY, ENGLAND, ASSIGNOR TO JACKSON BOILERS LIMITED, OF LEEDS, ENGLAND, A BRITISH COMPANY

WATER BOILER

Application filed December 30, 1926, Serial No. 158,042, and in Great Britain April 13, 1926.

This invention relates to water boilers, preferably self-feeding, of the type in which the water from a boiling chamber or interior is delivered up an expansion pipe into a collecting or expansion box or chamber to which is connected a draw off tap or the like, and has for its object to provide improved means for quickly and positively emptying the collecting or expansion box of any water remaining therein when the supply from the expansion pipe ceases.

Previously small weeping holes have been provided in the bottom of the collecting or expansion box for the purpose of emptying this box, but as they are necessarily small, various devices have been employed for keeping them clear of fur flakes, from becoming furred up or otherwise obstructed. The water passing through the weeping holes in previous constructions has gone direct to the bulk water supply chamber usual with this kind of boiler which generally is in the form of an outer annular case. The size of the weeping hole has necessarily been kept as small as possible, for if they were too large the bulk of the boiling water delivered by the expansion pipe to the collecting or expansion box would merely run back to the bulk water supply chamber instead of out of the draw off tap or the like.

In general according to the present invention means are provided for connecting the weeping hole with the expansion pipe or boiling chamber, which means may comprise a tube or other suitable fitting.

In this way when boiling water is being delivered into the collecting or expansion box by the expansion pipe it is also being caused to enter by the weeping hole. As a consequence it will be obvious that the water does not run out of the weeping hole simultaneously with the delivery into the collecting or expansion box and so a much larger weeping hole can be used. This quickly empties the said collecting box when the supply from the boiling chamber ceases.

The weeping hole when connected to the boiling chamber or interior may be connected to the upper portion thereof or may be connected to a point lower down. Instead of

having a separate weeping hole, the expansion pipe in place of being connected to the expansion or collecting box some distance above the bottom in the usual manner, may be connected to the bottom of the box in such a manner that when water is not being delivered up the expansion pipe any water remaining in the box immediately falls down the expansion pipe. In this way the opening of the expansion pipe into the expansion or collecting box forms the weeping hole and the expansion pipe itself forms the connection from the weeping hole to the interior or boiling chamber.

In order that the invention may be better understood it will now be described with reference to the accompanying drawings in which:—

Fig. 1 is an elevation partly in section of one form of self feeding water boiler constructed according to one method of carrying the invention into effect.

Fig. 2 is a similar view to Fig. 1 but showing another embodiment of the invention.

Fig. 3 is a plan of the expansion or collecting box and connections of the form of the invention shown in Fig. 2.

Fig. 4 shows somewhat diagrammatically a sectional elevation of the upper portion of a so-called fountain type of boiler with the invention applied thereto, and according to another method of carrying the invention into effect.

Fig. 5 shows somewhat diagrammatically the upper portion of another boiler illustrating a further embodiment of the invention.

Fig. 6 is a detail elevation, partly in section, of the tank and its controlling float and inlet and overflow openings.

The water boiler shown herein is used for obtaining quick supplies of boiling water in restaurants, tea-shops and other similar places and it is imperative when the outlet tap 11 is turned on the boiling water should be supplied immediately.

The boiler comprises an outer jacket 6 which is fed automatically from a tank 7 which comprises an automatic supply valve such for example as a float valve 29 controlled

by float 26. Said tank also has an overflow opening 27 and an inlet opening 28. Said float operates an inlet controlling valve 29. The boiler further comprises an inner boiling chamber 8 connected at its lower end with the jacket 6. The level in the chamber 8 and jacket 6 is kept constant by the supply from the cistern 7 and this level comes just about at the base of the expansion and bubbling box or collecting chamber 10. The water is heated by means of a gas ring (not shown) or the like at the lower part thereof beneath the boiling chamber 8 the gas supply being controlled by a gas valve the handle of which is operated to turn the gas full on when the tap 11 is open and when the tap 11 is closed to lower the gas. The boiling water by expansion and ebullition rises up the pipe 9 termed the expansion pipe and enters the collecting chamber 10 from which it passes to the tap 11.

A defect of the arrangement described is that when the tap 11 is closed a certain amount of boiling water remains in the collecting chamber 10. This becomes cooler and when the tap 11 is again opened it lowers the temperature of the next supply of boiling water passing up the pipe 9 into the chamber 10, and as a consequence the first part of the supply when the tap 11 is turned on is below boiling point.

It therefore became imperative that means should be devised for draining away water remaining in the collecting chamber 10 after the tap 11 was closed; for this purpose small holes or a small hole have been heretofore made in the lower portion of the chamber 10 termed "weeping holes". As these weeping holes were fairly small means had to be devised for keeping them clear of encrustation or flakes of fur or the like.

According to my invention I connect the weeping hole at the lower portion of the collecting box or chamber to the boiling chamber directly by suitable means such as a pipe or the like or through the actual expansion pipe as hereinafter described and claimed.

The upper portion of the boiling chamber or interior 8 is connected to the expansion pipe 9 by a conical member 12 which carries by means of an apertured plate or spider 13 the upper open end 14 of a displacer 16 formed as a cone 17 on the interior and as a cylinder 18 on the exterior and with an open lower end 19 of larger size than the opening 14. By the provision of the displacer 16 increased velocity is given to the water passing upwards therethrough during the boiling of the water in the chamber 8, owing to the cone 18. The water passing through the apertures in the plate 13, also increases the velocity and the increasing velocity generally sets up turbulences greater than hitherto in the irregular portions of the chamber 8 and finally the conical member 12 further

increases the velocity of the boiling water which passes to the expansion pipe. In this manner the excessive formation and accumulation of fur has been avoided and it has been found that a boiler constructed with a displacing member as described does not form or accumulate fur to anything like the extent with similar boilers without the displacer.

The expansion box or collector 10 is provided at the bottom with a weeping hole 20 of comparatively large size connected by means of a pipe 21 with the interior of the boiling chamber 8. Although the drawing shows the pipe 21 connected to the upper portion of the chamber 8 it may be connected lower down in any suitable position.

In action it will be understood that any boiling water left in the box 10 when the draw off cock 11 is closed will pass through the weeping hole 20 into the pipe 21 to the boiling chamber 8 and, as the weeping hole 20 is of comparatively large size, the water will pass away quickly. When the draw off cock 11 is open and boiling water is passing up the expansion pipe 9 to the expansion box 10, it will be readily understood that boiling water is passing up the pipe 21 and thus greater delivery to the box 10 is assured.

In the form of the invention shown in Figs. 2 and 3 the expansion pipe 9^b opens at 22 into the expansion box 10^b, the weeping hole 20^b is located at the bottom of the box 10^b and communicates by a pipe 23 with the expansion pipe 9^b.

The arrangement of the expansion box and connections thereof are preferably as shown in plan in Fig. 3. From this it will be seen that the opening 22 of the expansion pipe comes towards one end of the box 10^b while the weeping hole 20^b comes at the other end and that the draw off opening for the cock 11^b is located substantially midway between the openings 22 and 20^b.

To facilitate cleaning, a removable plug 24 is provided at the elbow of the expansion pipe 9^b. This plug is secured in position by suitable screws and when removed enables the expansion pipe and parts connected thereto to be cleaned.

In Fig. 4 the weeping hole 20^a is located in the bottom of the expansion box 10^a and opens directly into the expansion pipe 9^a, in other words the expansion pipe both acts for the delivery of the boiling water from the boiling chamber or interior to the expansion box 10^a and also when it ceases to deliver boiling water acts to drain the expansion box or collector 10^a.

A somewhat similar construction to that shown in Fig. 4 is shown in Fig. 5 but instead of being applied to the fountain type of boiler it is applied to a boiler more of the type shown in Figs. 1 and 2. In this case it will be seen that the expansion pipe 9^c is of curved shape and connected to the upper portion of

the boiling chamber by means of an elbow or the like 25. The collecting chamber is indicated at 10°. The form of the invention shown in Fig. 5 acts in exactly the same manner as that described with reference to Fig. 4.

5 Although the particular forms of the invention shown in the drawings are applied to boilers with gas heating means, it is obvious that boilers with other heating means such for example as electrically heated may also 10 be constructed according to the invention.

The invention is not limited to the particular forms or details of construction described as these may be varied to suit particular cases.

15 What I claim and desire to secure by Letters Patent of the United States of America is:

In apparatus of the class described, a boiler comprising an outer water jacket and an interiorly arranged boiling chamber, an expansion pipe leading upwardly from said boiling chamber, a collector into which the expansion pipe discharges, said collector being provided with a tap, and a duct of restricted 20 capacity connecting the lower portion of the 25 collector to the boiling chamber and means to supply said outer water jacket with water.

In witness whereof I affix my signature.
HAROLD HARGREAVES.
